PERMANENTLY ATTACHED CLOSURE
DEVICE FOR CONTAINERSWalter J. Dixon, United States Army,
Fort Lee, Va.

Application January 4, 1952, Serial No. 265,025

5 Claims. (Cl. 222—92)

(Granted under Title 35, U. S. Code (1952),
sec. 266)

1

The invention described herein, if patented, may be manufactured and used by or for the Government for governmental purposes, without the payment to me of any royalty thereon.

My invention relates to closure means for collapsible containers and the like.

A primary object of the invention is to provide a closure device for collapsible tubes of toothpaste or the like which is permanently connected to the neck of the tube and cannot be misplaced or lost.

A further object is to provide a closure element for collapsible containers which is highly simplified in construction and embodying a novel and simplified mode of operation.

A further object of the invention is to provide a closure element of the above-mentioned character which is not likely to become clogged with the toothpaste or the like.

Other objects and advantages of the invention will be apparent during the course of the following description.

In the accompanying drawings forming a part of this application, and in which like numerals are employed to designate like parts throughout the same,

Figure 1 is a fragmentary perspective view of a collapsible tube equipped with closure means embodying my invention, said means being arranged to cover the dispensing opening of the tube,

Figure 2 is a similar view showing the closure means in an open position,

Figure 3 is a central vertical longitudinal section through the closure means while positioned as in Figure 1, parts in elevation,

Figure 4 is a transverse vertical section taken on line 6—6 of Figure 3,

Figure 5 is a central vertical longitudinal section through the closure device when the same is turned 90° with respect to the collapsible tube,

Figure 6 is a horizontal cross section taken on line 6—6 of Figure 5,

Figure 7 is a transverse vertical section taken on line 7—7 of Figure 5,

Figure 8 is a fragmentary horizontal section on line 8—8 of Figure 3, and

Figure 9 is a side elevation on a reduced scale of closure means embodying a modification of the invention.

In the drawings, where for the purpose of illustration are shown preferred embodiments of my invention, attention is directed first to Figures 1 to 8 inclusive, wherein the numeral 15 designates a collapsible container or tube for tooth-

2

paste or the like, having an upper end 16, provided with a central reduced cylindrical neck 17. Formed upon the upper end of the reduced neck 17 is an enlarged annular head or flange 18 which is relatively thin, compared to the axial length of the neck 17, but extending radially beyond the periphery of the neck for forming an annular shoulder 19. The head 18 has a dispensing aperture 20 formed centrally therein which may be rectangular, as shown, round or any other desired shape.

Formed upon the neck 17 and preferably integral therewith is a pair of diametrically oppositely disposed locking cams or wedges 21 and 22. The wedges 21 and 22 are elongated circumferentially of the neck 17 and project radially beyond the neck and preferably have their outer curved sides arranged a slight distance inwardly of the periphery of the head 18, Figure 6. Each wedge 21 and 22 preferably extends circumferentially of the neck 17 for a substantial distance such as 60°, although the circumferential lengths of the wedges may be varied as found desirable. The wedges 21 and 22 have inclined lower faces 23, for a purpose to be described. The wedges 21 and 22 are tapered, and have their leading or tapered ends 24 facing in the same direction and arranged substantially diametrically opposite each other, as shown. The rear ends 25 of the wedges are likewise arranged diametrically opposite each other and the inclined face 23 of each wedge is spaced the same distance below the shoulder 19. The entire neck 17, including the head 18 and wedges 21 and 22 may be formed of metal, moldable plastics material or the like. The neck 17 is built into the collapsible tube 15 during the manufacture of the latter and forms an integral part of the same.

A closure cap or slide 26 is provided and preferably formed of a moldable plastics material, or the like. The cap 26 is rectangular and somewhat elongated as shown in the drawings, and includes top and bottom flat walls 27 and 28, longitudinal sides 29 and ends 30, all integrally connected. The top wall 27 is provided near and inwardly of one end 30 with a circular opening 31 slightly larger than the diameter of the head 18 and adapted to permit passage of the head therethrough when the cap 26 is in the open position, Figure 2. Except for the opening 31, the top wall 27 is imperforate, as are the longitudinal sides 29 and ends 30.

The bottom wall 28 of the cap 26 is provided with a longitudinal slot 32, having its opposite ends 33 circularly curved as shown. One cir-

cularly curved end 33 is formed concentric with the opening 31 of the top wall 27, as best shown in Figure 6, and this end 33 is spaced a substantial distance from the corresponding end 30 of the cap. The other end 33 is spaced a lesser distance from the other end 30, Figure 6, so that slot 32 is offset longitudinally toward the end 30 of the cap remote from the opening 31. The radii of the slot ends 33 are slightly greater than the radius of the neck 17 so that the neck can freely enter and pass from each curved end 33, while moving longitudinally within the slot 32. The width of the slot 32 is slightly greater than the diameter of the neck 17, and sufficient clearance is provided to permit the cap 26 to be shifted freely with respect to the neck.

The parallel longitudinal edges of the slot 32 are spaced laterally inwardly of the sides 29 and form narrow longitudinal flanges 34, integral with end shoulders 35 and 36, Figure 3.

The distance between the longitudinal sides 29 is slightly greater than the diameter of the head 18, and the head is freely slideable longitudinally within the cap 26. The distance between the top and bottom walls 27 and 28 of the cap is slightly less than the combined thickness of the head 18 and wedges 21 and 22, at the thick ends 25 of the wedges. The cap 26 is permanently connected with the neck of the tube 15 and cannot be accidentally removed or lost, since the enlarged head 18 cannot pass through the opening 31.

In operation, assuming that the cap 26 is positioned as in Figures 1, 3 and 4 for covering the dispensing aperture 20, the neck 17 is arranged within the end 33 of the slot 32 remote from the opening 31, and the head 18 is substantially contacting the adjacent end 30. The locking cams or wedges 21 and 22 are now engaging upon the flanges 34, and holding the top of the head 18 tightly against the imperforate portion of the top wall 27, which covers the aperture 20. Since the combined thickness of the wedges 21 and 22 and the head 18 is slightly greater than the distance between the top and bottom walls 27 and 28, the head 18 is held in tight frictional engagement with the top wall 27 and the cap 26 is frictionally locked against movement with respect to the neck of the tube.

When it is desired to open the tube, the cap 26 is first turned 90° about the neck 17 from its position in Figures 1, 3 and 4, and this movement positions the wedges 21 and 22 transversely of the slot 32 and free from engagement with the shoulders 34. The frictional engagement of the top wall 27 and head 18 is now broken and the head 18 is free to move downwardly until the shoulder 19 contacts flanges 34, the transversely extending wedges 21 and 22 now being passable through the slot 32, Figure 6. With the cap turned 90° from its position of Figure 1, the cap is shifted longitudinally until the head 18 registers with the opening 31, and the neck 17 engages the slot end 33 which is concentric with and below the opening 31, as shown dotted in Figure 3. When this position is reached, the entire cap 26 is shifted downwardly upon the neck 17, until the head 18 projects above the top wall 27, as shown in Figure 2. The downward movement of the cap 26 is limited by contact with the top 16 of the tube.

With the cap positioned as shown in Figure 2, the collapsible tube 15 is squeezed for dispensing toothpaste or like contents, and there is small probability of the paste entering the opening 31.

and clogging the interior of the cap 26, since the head 18 and aperture 20 are now spaced a substantial distance outwardly of the top wall 27.

When it is again desired to cover the dispensing aperture 22, the cap 26 is first elevated until the head 18 passes through the opening 31 to the interior of the cap. The cap is now shifted longitudinally in the opposite direction until the head 18 engages the opposite end 30 and the neck 17 reaches the corresponding slot end 33. The cap 26 is now held down, so that the top wall 27 contacts the head 18, and the cap is turned clockwise 90° about the neck 17, as viewed in Figures 6 and 8. When this is done, the tapered wedges 21 and 22 ride up onto the flanges 34 and the head 18 is forced upwardly into tight frictional engagement with the top wall 27. The aperture 20 is now covered by the imperforate portion of the top wall 27, and the cap 26 is frictionally locked against movement.

In Figure 9, there is shown a modification of the invention, wherein a collapsible tube 15' has the usual externally screw-threaded neck 37, through which toothpaste, or the like, is dispensed. An adapter tube 38 is provided, and has a screw-threaded opening 39 in its lower end, receiving the neck 37, after the conventional screw-cap has been removed and discarded. Axially beyond the screw-threaded opening 39, the adapter tube 38 is formed exactly like the neck 17, and provided with the identical head 18 and locking cams 21 and 22, for coaction with the identical cap 26 shown and described in connection with the first form of the invention. In the form of the invention shown in Figure 9, the adapter tube 38 renders it possible to use a standard collapsible tube having a conventional screw-threaded neck, and it is unnecessary to form a special neck upon the tube. The conventional screw-cap is merely removed and discarded and replaced by the adapter tube 38 which has the slide or cap 26 permanently connected therewith. The use and operation of the device shown in Figure 9 is identical with that in the first form of the invention.

It is to be understood that the forms of the invention herewith shown and described are to be taken as preferred examples of the same, and that various changes in the shape, size and arrangement of parts may be resorted to, without departing from the spirit of the invention or scope of the subjoined claims.

Having thus described my invention, I claim:

1. Closure means for a collapsible container having a neck provided with an enlarged head comprising a body portion having top and bottom walls, sides, and ends, said bottom wall having a longitudinal slot receiving the neck of the container and being narrower than the enlarged head so that the head cannot pass through the slot, the top wall of the body portion having an opening opposite one end of the slot larger than said head and allowing passage of the enlarged head outwardly of said top wall, there being longitudinal flanges formed on said bottom wall and projecting inwardly of the sides of the body portion, and a pair of tapered cam elements formed upon the neck near opposite sides of the same and disposed below the enlarged head and adapted to engage the flanges for forcing the head into engagement with the top wall of the body portion.

2. In a collapsible container, a neck having an enlarged head provided with a discharge opening, a closure element mounted upon the neck and in-

cluding spaced inner and outer walls, the outer wall having an opening near one end of the closure element adapted to receive the enlarged head, the inner wall having a slot receiving the neck of the container and forming with said inner wall opposed longitudinal flanges which prevent the passage of the enlarged head through the slot, the closure element being shiftable transversely of the neck to position the enlarged head adjacent to the opening of the outer wall, whereby the enlarged head may pass through said opening when the closure element is shifted inwardly upon the neck, and a cam element secured to the neck inwardly of the enlarged head for engagement upon one of said longitudinal flanges when the closure element is turned about the neck while the enlarged head is arranged inwardly of the outer wall.

3. A closure device for a collapsible container having a screw-threaded neck comprising a tube provided in one end with a screw-threaded opening receiving the neck, the other end of the tube being provided with an enlarged head having a discharge opening, a cam element formed upon the tube near and inwardly of the head, and a closure member permanently connected with the tube and shiftable transversely thereof to open and closed positions, said closure member including inner and outer walls, the outer wall having an opening receiving the enlarged head of the tube, the inner wall having a slot receiving the tube and being narrower than the enlarged head, the slot forming with the inner wall a flange extending longitudinally of the closure member upon which the cam element engages when the closure member is turned about the tube and the enlarged head is arranged inwardly of said outer wall.

4. In a collapsible container a tubular discharge extension through which the contents of the tube are dispensed when the container is compressed, said extension being provided near its outer end with an enlarged head, a pair of diametrically opposed tapered cam elements formed upon the extension near and inwardly of the enlarged head, and an elongated closure element permanently connected with the extension and including inner and outer walls, the outer wall having an opening near one end of the closure element to receive the enlarged head, the inner wall having a longitudinal slot narrower than the opening of the outer wall, one end of the

slot being opposite said opening, the slot receiving the extension and permitting the closure element to be shifted transversely of the extension, the tapered cam elements engaging above the inner wall on opposite sides of the slot when the closure element is turned about the extension while the enlarged head is disposed inwardly of the outer wall, the enlarged head being then forced against the outer wall of the closure element.

5. A collapsible container comprising a body portion, a reduced cylindrical neck secured to the body portion and having a discharge passage for the contents of the body portion, a relatively thin cylindrical head secured to the outer end of the neck and having a diameter greater than the neck, tapered cam elements secured to the neck inwardly of the head and being spaced apart circumferentially of the neck and projecting radially beyond the periphery of the neck and having their outer sides arranged near the periphery of the cylindrical head, and a closure slide permanently connected with the neck and including spaced inner and outer walls, said inner wall of the closure slide having a slot receiving the neck and permitting the closure slide to be shifted transversely of the neck, the slot being narrower than the head so that the head cannot pass through the slot, the outer wall of the closure slide being arranged outwardly of the head and having an opening formed therein adjacent to one end of the slot so that the head may pass through the opening when the neck engages said one end of the slot, the tapered cam elements being adapted to engage upon said inner wall at opposite sides of the slot when the neck engages the other end of the slot and the closure slide is turned circumferentially about the neck, the cylindrical head being then shifted into engagement with the outer wall of the closure slide and the opening of said outer wall then being out of registration with the head.
